CLAIM

The ornamental design for a toothbrush, as shown and described.

DESCRIPTIONFIG. 1 is a $\frac{3}{4}$ perspective view of a toothbrush showing the top left and distal end of the first embodiment of the toothbrush of the present invention;

FIG. 2 is a reduced left side elevational view of the brush of the present invention, the right side being a mirror image;

FIG. 3 is a reduced top plan view thereof;

FIG. 4 is a reduced bottom plan view thereof;

FIG. 5 is a reduced view from the head end thereof;

FIG. 6 is a reduced view from the handle end thereof;

FIG. 7 is a perspective view of a second embodiment of the design shown in FIGS. 1-6, the only difference residing in the absence of three grip pads on the top of the handle;

FIG. 8 is a perspective view of a third embodiment of the design shown in FIGS. 1-6, the only difference residing in the lengths of the head and the handle and the number of bristle tufts extending from the head.
